ROBERT J. SMITH, OF YONKERS, NEW YORK, ASSIGNOR TO OTIS ELEVATOR COMPANY,
OF JERSEY CITY, NEW JERSEY, A CORPORATION OF NEW JERSEY.

AIR DRILL-SOCKET.

1,028,623.

Specification of Letters Patent. Patented June 4, 1912.

Application filed September 27, 1907. Serial No. 394,849.

To all whom it may concern:

Be it known that I, ROBERT J. SMITH, a citizen of the United States, residing in Yonkers, in the county of Westchester and 5 State of New York, have invented a new and useful Improvement in Air Drill-Sockets, of which the following is a specification.

This invention relates to air-drill-sockets, 10 and one of its objects is the provision of an improved form of construction in which air or other fluid is conveyed through the socket and to the point of the drill for the purpose of blowing out the chips formed by the drill, and also keeping down the temperature of 15 the drill.

The invention further aims to provide a construction in which the friction between the stationary and moving parts of the air- 20 drill-socket is reduced to a minimum, in which frequent lubrication is unnecessary, and in which excessive leakage of air, and excessive heating are avoided.

A still further object of the invention is 25 the provision of a construction in which the air or other fluid is supplied to opposite sides of the drill simultaneously in order to avoid a one-sided pressure on the drill and the consequent friction and binding.

30 Other objects of the invention will appear more fully hereinafter, the novel combinations of elements being pointed out in the appended claims.

Referring to the drawings in which is 35 illustrated a preferred embodiment of my invention, Figure 1 is an elevation partly in section of the air-drill-socket and drill; Fig. 2 is a section on the line II-II of Fig. 1; Fig. 3 is a bottom plan view of Fig. 1; and 40 Fig. 4 is a fragmentary view of the drill-socket.

In the operation of drills now in common use, great difficulty is experienced on account of the drill becoming quickly clogged 45 up with the chips or cuttings which necessitates the frequent withdrawal of the drill to clear away the cuttings. This is especially true in drilling holes of considerable depth. As the drill clogs up, its progress is 50 retarded and the material ground up much finer, requiring an increased expenditure of energy and causing excessive heating. Attempts have been made to overcome these objections by the use of compressed air, or 55 other fluid under pressure, but the devices

used for this purpose have been found to be impracticable or inefficient on account of excessive leakage of air, and the friction of the bearings. The form of air-drill-socket shown in the accompanying drawings is designed to overcome these objections. The term air-drill-socket is applied to the device in its entirety, except the drill, and includes the drill-socket, roller-bearings, case, and the supply pipe P, these parts forming a 65 unitary structure with which a drill may be used.

The drill D is of a form well-known to those skilled in the art, and I do not make any claim to the drill *per se*. The drill- 70 socket A in its general construction is also of a well-known form except for modifications adapting it to my invention as will fully appear hereinafter.

The drill D is received in the drill-socket A, which in turn is mounted for rotation in a non-rotating roller bearing case C, which latter is preferably made of brass but may be made of any other suitable material. The body portion 2 of the drill-socket which 75 is cylindrical in form, has its lower part cut down or of smaller diameter to form a reduced cylindrical portion 1, the junction of these two parts forming a flange or shoulder 80 3. The drill D extends upwardly through 85 a tapered bore in the socket corresponding to the tapered portion of the drill.

The roller-bearing case C is cylindrical in form and has an integral top portion provided with an opening to receive and fit 90 loosely on the drill socket which rotates in the case C. The case C has a removable bottom or cover 4, also preferably made of brass and secured in position by screws 5. Within the case are the roller bearings 95 which comprise the steel rollers 6 having bearings in the roller cage which comprises upper and lower rings 7 and 7', respectively, and vertical guides or spacing members 8 conforming to the shape of the rollers, and preventing displacement but allowing free 100 rotation of the rollers. Between the portion 1 of the drill-socket, and the rollers 6 is a hardened steel ring or sleeve 9 which fits tightly on the socket, and between the case C and the roller 6 is a similar ring or sleeve 10 of hardened steel which fits tightly in the case. The rings 9 and 10 form bearing surfaces for the inner and outer portions respectively of the bearing rollers. This construc- 111

tion permits a free rotation of the drill and its socket in the case C, and at the same time prevents lateral play, and also prevents binding and reduces friction to a minimum.

5 A ring or washer 11, preferably made of vulcanized fiber, is placed between the ring 7 and the top of the case C, and also extends under the shoulder 3. This washer is clamped between the sleeve 9 and the socket 10 and rotates therewith. An important function of the washer is to prevent leakage between the top of the casing and the drill socket. Another purpose of the washer is to prevent wear of the metallic parts. The 15 washer being made of fiber or non-metallic substance does not cut or wear the metallic parts even when no oil is present. The washers are inexpensive and when worn can readily be replaced by new ones. A similar 20 ring or washer 12 also made of fiber is placed between the ring 7' and the bottom 4 of the case. This ring is set into a recess in the bottom 4 so as to be flush with the upper surface thereof, and extends beneath 25 both the rings 9 and 10. With this arrangement, only little lubrication is required, and that only at long intervals.

An oil hole 13 extending through the top of the casing provides a means for lubricating the bearings. This oil hole may be closed by a small screw 14 to prevent the entrance of dust and dirt, and also to prevent leakage of air.

The means for supplying the drill point 35 with compressed air will now be described.

The drill D is provided in its periphery with a spiral groove or grooves 15 which extend from the drill point to a point near the shank of the drill. Lateral openings 16 40 extend inwardly from the surface of the drill shank, and these openings 16 communicate with the grooves 15 through passageways or openings 17 extending between the openings 16 and grooves 15. Air tubes 18 45 are placed in the grooves 15 and extend from the drill point into the passageway 17. The grooves 15 are preferably set deep enough in the drill and surround the tubes 18 for a sufficient distance to prevent lateral 50 displacement of the tubes, and also to retain the tube completely within the periphery of the drill.

Compressed air from any suitable source is supplied through a pipe 20 (Fig. 3) to 55 a rectangularly branched pipe P communicating with the drill through opposite sides of the bottom 4 of the casing. The pipe P comprises elbow joints a, b, c, d, T-joint 21, connecting the supply-pipe 20 with the pipe P, joints 22 between the T-joint 21 and the joints a, b, joints 23 provided with right and left handed screw threads for connecting the two sides of the pipe P through short sections 24, and short sections or nipples 25. 60 The nipples 25 are provided with screw

threads on their inner sides to fit correspondingly threaded openings 26 in the bottom 4 of the case C. In the central opening in the cover 4 which receives the drill socket A, is an annular groove 27 surrounding 70 said socket. Air passages 28 extend from the groove 27 to the opening 26. The drill socket is provided with openings 29 which communicate with the groove 27 and the openings 16. The inner surface of the drill 75 socket is preferably provided with an annular groove or recess 30 connecting the openings 29. This groove is for the purpose of providing an air passage between the opening 29 and 16 in case said openings are not in line when the drill is in position in the socket. The drill socket which fits closely in the cover 4, forms with the groove 27 an air passage which connects the openings 28 and 29 for all positions of the 80 drill socket. It will thus be seen that when the drill is in operation there is a constant stream of air at the drill point so long as air is supplied to the pipe 20.

It will be observed that the only parts 90 that have relative movement and between which the air might escape, are the drill socket and the cover 4. As these parts have large bearing surfaces, and the construction admits of a close fit between them, there will be little leakage of air at this place, and this leakage is further reduced by the fiber washers preventing the escape of air in an upward direction through the case C. As other joints in the air passages may readily 95 be made air tight it follows that the air will be directed with little loss to the point where it can be utilized, even when it is supplied under considerable pressure.

An important feature of my invention is 105 the arrangement of the pipes to supply air at opposite sides of the drill, thus equalizing the lateral pressure of the air on the drill and preventing the friction and binding incident to a one-sided pressure.

With the construction shown the friction between the rotating drill socket and the relatively stationary case C is so slight that there is little tendency for the case to rotate and such rotation is ordinarily prevented by 115 the flexible supply tube which is connected to the pipe P. There is therefore no need of any special appliances for holding the case against rotation.

In assembling the parts the washer 11 is 120 placed in position on the drill-socket. The bearing sleeve 9 is shrunk, driven, or otherwise firmly secured to the socket 1 so as to rotate therewith. If desired, the washer 11 may be held rigidly against the shoulder 3 125 so that the said washer will also rotate with the socket 1 and the sleeve 9. The roller bearing cage and bearings may then be placed in position over the sleeve 9. The case C with the sleeve 10 which is forced into position 130

therein, is brought down over the top of the drill socket into position over the roller bearings, and the cover 4 may then be secured in place.

5 In operation a constant stream of air is supplied at the point of the drill sufficient to blow out all the cuttings and prevent clogging at the same time keeping the drill cool. As a practical result, a number of drills may 10 be used in one machine for drilling a number of holes in a casting at once, as the drills are each kept free and cool and will operate without binding or clogging during the entire drilling of a set of holes of any required 15 depth.

Although I have referred to the device as an air-drill-socket and have described its use in connection with compressed air, it is to be understood that oil may be used and sometimes is used in place of air, also that water or any other suitable fluid might be used. However, my improvement is particularly adapted to the use of drills when compressed air is used. Heretofore no successful means 25 for transmitting the compressed air through the drill socket have been devised. The part in which the drill socket rotates requires at least a little lubrication, and I have found that by the arrangement herein disclosed, 30 sufficiently air tight connections may be maintained to prevent the compressed air from blowing out the lubricant and causing the drill socket to stick in the holder, and thereby prevent rotation.

35 Important features of my invention are, that air tight connections are obtained and the friction reduced to a minimum by the roller bearings, and what little lubricant is used on such roller bearings is not blown out 40 by the compressed air, by reason of the air tight connections.

If desired, the shoulder 3 may be the under side of a collar or ring fastened to the socket 1. Or such a ring may be fastened to 45 the socket 1 of uniform diameter throughout, the washer 11 placed above the same, and the upper horizontal portion of the casing C allowed to rest on the washer. I may also omit the inner and outer sleeves 9 and 50 10 and harden the socket 1 and casing C to withstand the wear. In some instances, however, it may be more economical to employ a socket 1 and casing C of comparatively soft metal and have the sleeves 9 and 55 10 of sufficiently hard metal to withstand the wear of the roller bearings. Furthermore, I may substitute for the roller bearings one or two sets of ball-bearings which may also act as thrust-bearings. Also, if 60 desired, the air may be admitted at other points than those shown, but, in any event, the admission of the air should be such that it will not cause any binding of the socket within the cover 4. In other words, it is im- 65 portant that the air be admitted at opposite

sides to reduce friction of the socket 1 within the parts with which it comes in contact. Whatever the arrangement as to details, it is evident that the roller bearings and its casing supported by the washer 11 will move 70 up and down with the drill, and the drill socket only will rotate with minimum friction while compressed air is being supplied with equal pressure on opposite sides of the drill, and thence transferred to the drill point, so that holes of considerable depth 75 may be drilled in all kinds of material.

I have shown and described a practical embodiment of my invention, but I do not wish to be limited to the exact form of construction shown, as various changes in details and arrangements of parts might be made within the spirit and scope of the invention as defined in the appended claims.

What I claim as new and desire to secure 85 by Letters Patent of the United States, is:—

1. In an air-drill-socket, the combination with a drill socket formed with its lower end of reduced diameter, of a bearing sleeve surrounding the reduced portion, a roller 90 cage and bearing rollers therein surrounding said sleeve, a second bearing sleeve surrounding the rollers, a case inclosing the rollers and having its top loosely fitting around the portion of the socket of larger 95 diameter, a washer between said top and the rollers and extending across the line of contact between said top and socket, and a second washer between the bottom of the case and the bearing sleeve. 100

2. In an air-drill-socket, the combination with a drill socket, of a stationary member surrounding the socket, one of said parts being formed with a recess surrounding the socket, and the socket being formed with an opening extending therethrough from said recess, air passages on opposite sides of the socket leading from the recess to the outer surface of said member, and pipes connecting said passages to a source of air supply. 105 110

3. In an air-drill-socket, the combination with a drill-socket formed with an annular shoulder, of a case in which the socket is rotatably mounted and having an inner surface flush with said shoulder, said parts being formed with an air passage therethrough, and a non-metallic ring or washer extending across the joint between the socket and case. 115

4. In an air-drill-socket, the combination with a drill-socket formed with one portion of reduced diameter, of a stationary member in which the socket is mounted for rotation, and a non-metallic substantially flat washer surrounding the reduced portion of the socket and extending across the joint between the socket and the stationary member, said socket and member being formed with communicating air passages extending therethrough. 120 125 130

5. In an air-drill-socket, the combination of a drill-socket, and a member in which the drill-socket is mounted for rotation, said member being provided with a number of 5 passages for supplying compressed air to the drill socket, said passages being so disposed that the distances between said passages as measured around the circumference of the drill socket are substantially equal.

10 6. In an air-drill-socket, the combination with a drill-socket, of a member in which the drill-socket is mounted for rotation, and means for supplying compressed air through said member to opposite sides of the drill 15 socket.

7. In an air-drill-socket, the combination with a drill-socket of a stationary bearing member in which the drill socket is mounted for rotation, said bearing member being 20 formed with compressed air openings extending therethrough to opposite sides of

the socket, and said socket being formed with an opening therethrough.

8. In an air-drill-socket, the combination with a stationary bearing member, a drill-socket mounted for rotation in said member, said socket and bearing member being formed with an annular groove surrounding the socket, openings through the bearing member to said groove at opposite sides of 25 the socket, and openings extending from the groove to the interior of the socket, and means for connecting the openings in the bearing member to a source of compressed air supply. 30

In testimony whereof, I have signed my name to this specification in the presence of two subscribing witnesses.

ROBERT J. SMITH.
